HYDRAULIC TABLE RECIPROCATING MECHANISM

Donald H. Holmes, Worcester, Mass., assignor to
 Norton Company, Worcester, Mass., a corpora-
 tion of Massachusetts

Application June 13, 1945, Serial No. 599,184

5 Claims. (Cl. 121—45)

1

The invention relates to grinding machines, and more particularly to a hydraulically operated table reciprocating mechanism for a grinding machine.

One object of the invention is to provide a simple and thoroughly practical table reciprocating and reversing mechanism. Another object of the invention is to provide a table reversing mechanism with an improved hydraulically operated dwell control mechanism. Another object of the invention is to provide a table reversing mechanism with a hydraulically operated variable dwell control mechanism whereby a variable dwell may be obtained at either or both ends of the reciprocatory stroke of the table. A further object of the invention is to provide a hydraulically controlled dwell control mechanism for delaying the shifting movement of the reversing valve into its reverse position. A further object of the invention is to provide a hydraulically operated table reciprocating mechanism with a hydraulically operated time delay control for the table reversing valve to control the extent of dwell at each end of the table stroke. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

The accompanying drawing, showing one of the various possible embodiments of the mechanical features of this invention, in which Fig. 1 illustrates a diagrammatic showing of a hydraulic control system of the improved table reciprocating mechanism.

Fig. 2 is a longitudinal sectional view, on an enlarged scale, of the table control valve and the dwell control unit, together with connecting piping, each being illustrated on the same relative scale.

As illustrated in the drawing, the machine embodying this invention comprises a base 10 which supports a longitudinally reciprocable work table 11 on the usual V-way and flat way (not shown) for a longitudinal reciprocatory movement relative to the base 10. A fluid operated reciprocating mechanism is provided to reciprocate the table 11 comprising a fluid pressure cylinder 12 which is fixedly supported by a pair of bracket end caps 13 and 14 which are fixedly mounted on the under side of the table 11. The cylinder 12 contains a pair of spaced pistons 15 and 16

2

which are connected by a pair of hollow piston rods 17 and 18, respectively, with a pair of hollow brackets 19 and 20, respectively, mounted on opposite ends of the base 10.

The base 10 is preferably formed as a box-like structure containing in its lower portion a reservoir 21 for the fluid pressure system. Fluid is drawn from the reservoir 21 through a pipe 22 by means of a motor driven fluid pressure pump 23. The pump 23 forces fluid under pressure through a pipe 24 to a table control or reversing valve 25. A pressure relief valve 26 is connected in the pipe line 24 to facilitate passing excess fluid under pressure through a pipe 27 into the reservoir 21 so as to maintain a substantially uniform operating pressure within the hydraulic system.

The control valve 25 is a piston type valve having two parts which slide relative to each other. A slidably mounted valve stem 28 is provided with a pair of spaced valve pistons 29 and 30. A reduced cylindrical portion 31 of the valve stem 28 passes through a central aperture formed in a slidably mounted reversing valve member 32. The reversing valve member 32 is provided with spaced integrally formed valve pistons 33, 34 and 35. In the position of the valve parts as shown in Fig. 1, fluid under pressure passing through the pipe 24 enters a passage 36 in the valve casing and passes through a port 37 into a valve chamber 38 located between the valve pistons 33 and 34 and passes out through a port 39 and a pipe 40 into a chamber 41 formed within the hollow bracket 19, through the hollow piston rod 17, into a cylinder chamber 42 formed at the left-hand end of the cylinder 12.

In this position of the parts, fluid within a cylinder chamber 43 formed at the right-hand end of the cylinder 12 may pass through the hollow piston rod 18, through a chamber 44 formed within the bracket 20, through a pipe 45, through a port 46, into a valve chamber 47 located between the valve pistons 34 and 35, and out through exhaust ports 48 and 48a and through a pipe 49 to a manually operable start and stop valve 51. The exhaust ports 48 and 48a are offset relative to each other so that during the shifting movement of the valve piston 34, the exhaust of fluid from the cylinder into the exhaust pipe 49 is gradually cut off.

The start and stop valve 51 is preferably a combined start-stop and speed control valve and is preferably formed integral with the valve 25 but for the sake of simplicity of illustration, it has been illustrated diagrammatically in the

drawing as a separate unit. The valve 51 is preferably located in the exhaust side of the system so as to maintain a uniform fluid pressure on the operating side of the main cylinder 12 during the entire reciprocatory stroke of the cylinder 12 relative to the pistons 15 and 16. An exhaust pipe 54 is operatively connected at the right-hand end of the valve 51 to convey exhausting fluid back to the reservoir 21. The valve 51 comprises a valve stem 55 having formed integrally therewith valve pistons 56 and 57. The control valve 51 is arranged so that it may be moved longitudinally from the full line position as shown in the drawings into the broken line position. The valve stem 55 is provided with an actuating knob 58 by means of which the valve may be rotarily adjusted. The right-hand end face of the valve piston 57 is formed as an angular plane face. By a rotary adjustment of the valve stem 55, the position of the angular end face of the piston 57 may be adjusted so as to vary the aperture of the V-port 59 to the desired and predetermined extent when the valve is in a starting position and serves as a fine adjustment to cut off more or less of the exhaust of fluid from the system, thereby precisely to regulate the reciprocatory speed of the table 11.

In order that the valve piston 57 may be maintained in the desired adjusted position during starting and stopping of the table 11, a serrated portion 60 is formed integral with the valve stem 55. A spring-pressed arrow-pointed plunger 61 is supported by the casing of the valve 51 and is maintained in engagement with the serrated portion 60 during the axial movement without changing the speed adjustment thereof.

A manually operable start and stop lever 65 is pivotally supported on a stud 66 which is in turn supported in a projecting boss 67 formed integral with an apron 68 which is in turn fixedly supported on the front of the machine base. The control lever 65 is provided with a clearance aperture 69 which surrounds a sleeve 70. The sleeve 70 is rotatably supported on the valve stem 55 and is provided with a pair of diametrically opposed grooves 71 which are engaged by a pair of diametrically opposed studs 72 (only one of which is illustrated in the drawing) carried by the control lever 65. It will be readily apparent from the foregoing disclosure that when the control lever 65 is positioned as indicated in full lines in the drawing, the V-port 59 is closed so as to prevent movement of the table 11.

When it is desired to start the reciprocatory movement of the table 11, the control lever 65 is shifted in a counterclockwise direction into broken line position 65a. This movement shifts the valve stem 55 toward the left into the broken line position so that the valve piston 57 will wholly or partially open the V-port 59 to allow a predetermined exhaust of fluid from the table cylinder 12 and thus control the speed of movement of the table 11.

When the valve 51 is in a closed position, such as shown in the drawing, it is desirable to provide a suitable by-pass whereby fluid may readily pass from the cylinder chamber 42 into the cylinder chamber 43 and vice versa to facilitate a manual traversing movement of the table 11. A pipe 80 is connected between the port 39 in the valve 25 and the valve 51. Similarly, a pipe 81 is connected between the port 46 in the valve 25 and the valve 51. When the valve stem 55 is

moved toward the right into a table stop position (as shown in the drawing), a valve chamber 82 located between the valve pistons 56 and 57 is positioned so that fluid may readily pass between the pipes 80 and 81 to facilitate a free passage of fluid between the cylinder chamber 42 and the cylinder chamber 43 of the table cylinder 12 so that the table may be readily moved longitudinally without the necessity of overcoming fluid under pressure within the system.

A manually operable table traverse mechanism may be utilized such as, for example, that shown in the prior U. S. Patent No. 2,071,677, and may comprise a manually operable hand wheel and a 15 rack and gear mechanism for moving the work supporting table 11 longitudinally. This mechanism is not considered to be a part of the present invention and consequently has not been illustrated and described in detail. For further 20 details of the manually operable table traversing mechanism, reference may be had to the U. S. patent above referred to.

A table actuated mechanism is provided for initiating a shifting movement of the reversing 25 valve 25 comprising a reversing lever 85 which is mounted on the outer end of a rock shaft 86. The rock shaft 86 is journaled in suitable bearings (not shown) formed in the apron 68. A short downwardly extending lever 87 is fixedly 30 mounted on the inner end of the rock shaft 86. The lever 87 is provided with a stud 88 which rides in a vertically extending groove 89 formed in the valve stem 28. The reversing lever 85 is provided with a rearwardly extending stud 90 35 which is arranged in the path of a pair of adjustably mounted table dogs 91 and 92. The table dogs 91 and 92 are adjustably supported in a T-slot 93 formed in the front edge of the work supporting table 11.

It is desirable to provide a dwell control mechanism whereby the work table 11 may be stopped for a predetermined time interval at reversal so as to allow time to cause an infeeding movement of the grinding wheel before the table starts its movement in the reverse direction. This dwell control is preferably accomplished by retarding the shifting movement of the valve stem 28 and the reversing valve 32 of the control valve 25.

The valve 25 is provided with a valve chamber 100 located between the valve pistons 29 and 33 which serves to facilitate a shifting movement of the reversing valve 32 in a manner to be herein-after described. It should be noted that the differential effective areas of the pistons 29 and 33 serve to aid in the reversal of the valve 25. A port 101 operatively connects the valve chamber 100 with a pipe 102 which is in turn connected with a fluid operated dwell control mechanism 55 to be herein-after described. A port 103 connects fluid under pressure in the valve passage 36 with the valve chamber 100 during the shifting movement thereof.

Similarly, the valve 25 is provided with a valve 65 chamber 105 which is located between the valve pistons 30 and 35, which serves to facilitate a shifting movement of the reversing valve 32 in a manner to be herein-after described. The differential effective areas of the pistons 30 and 35 also serve to aid in the reversal of the valve 25. A port 106 operatively connects the valve chamber 105 with a pipe 107 which is operatively connected with the dwell control mechanism to be herein-after described. A port 108 connects fluid 70 under pressure in the valve passage 36 with the

valve chamber 105 during the shifting movement thereof.

A fluid operated dwell control unit 110 is shown on an enlarged scale relative to the remainder of Fig. 1 to clarify the illustration of the dwell control unit 110. The unit 110 is provided which comprises a piston 111 which is slidably mounted within a cylinder 112. The piston 111 is normally urged in a downward direction by a compression spring 113. When the valve stem 28 and the reversing valve 32 is moved toward the left, fluid in the valve chamber 100 is forced through the port 101, the pipe 102 and enters a cylinder chamber 114 to cause the piston 111 to move upwardly against the compression of the spring 113 until a port 115 is uncovered, which allows fluid under pressure within the cylinder chamber 114 to exhaust through a pipe 116 into a reservoir 117 within the dwell control unit. The rate of upward movement of the piston 111 is preferably controlled by regulating the exhaust of fluid from a cylinder chamber 118 formed at the upper end of the cylinder 112. Fluid exhausting from the chamber 118 passes out through a pipe 119 and through a needle valve 120 which exhausts fluid through a pipe 121 into the reservoir 117. It will be readily apparent from the foregoing disclosure that by regulating the needle valve 120, the speed of movement of the piston 111 may be readily controlled so as to retard the movement of the reversing valve 32 and thereby to regulate the period of dwell as desired.

As shown in Fig. 1, the table 11 will start movement toward the left as soon as the start lever 65 is moved into position 65a. This movement continues until the table dog 92 engages the stud 90 on reversing lever and moves it in a counter clockwise direction, positively moving the valve stem 28 together with valve pistons 29-30 and reversing valve 32 toward the right (Fig. 1). As the reversing valve moves away from the left-hand end cap of the valve casing, the capacity of the valve chamber 100 is increased sufficiently before port 101 is closed by valve piston 29 so that fluid within the chamber 114 may be exhausted by the downward movement of the piston 112 under the influence of the released compression of spring 113. In order to refill the cylinder chamber 118, a passage 122 is connected with the reservoir 117. A ball check valve 123 connects the passage 122 with a passage 124 which is connected with the cylinder chamber 118. Suction created by the downward movement of the piston 111 draws fluid through the ball check valve 123 to refill cylinder chamber 118 so that it is ready for the next dwell control action.

The fluid operated dwell control unit 110 is also provided with a piston 127 which is slidably mounted within a cylinder 128. The piston 127 is normally urged in a downward direction by a compression spring 129. Fluid under pressure passing through the pipe 107 enters a cylinder chamber 130 and causes the piston 127 to move upwardly against the compression of the spring 129 until a port 131 is uncovered, which allows fluid under pressure within the cylinder chamber 130 to exhaust through a pipe 132 into the reservoir 117 within the dwell control unit. The rate of upward movement of the piston 127 is preferably controlled by regulating the exhaust of fluid from a cylinder chamber 133 formed in the upper end of the cylinder 128. Fluid exhausting from the cylinder chamber 133 passes out through a pipe 134 and through a needle

valve 135 which exhausts fluid through a pipe 136 into the reservoir 117. It will be readily apparent from the foregoing disclosure that by regulating the needle valve 135, the speed of movement of the piston 127 may be readily controlled so that the period of dwell may be regulated as desired.

When the table is moved toward the right, the table dog 91 engages the stud 90 on the reversing lever 85 and shifts the reversing lever 85 in a clockwise direction positively moving the valve stem together with valve pistons 29-30 and reversing valve 32 toward the left (Fig. 1). As the reversing valve moves away from the right-hand end cap of the valve casing, the capacity of the valve chamber 105 is increased sufficiently before the port 106 is closed by valve piston 30 so that fluid within the chamber 137 may be exhausted by the downward movement of the piston 127 under the influence of the released compression of spring 129. In order to refill the cylinder chamber 133, a passage 137 is connected with the reservoir 117. A ball check valve 138 connects the passage 137 with a passage 139 which is connected with the cylinder chamber 133. Suction created by the downward movement of the piston 127 draws fluid through the ball check valve 138 to refill the cylinder chamber 133 ready for the next dwell control action.

As illustrated in Fig. 2, the capacity of the valve chambers 100 and 105 increases sufficiently during the shifting of the reversing valve to allow sufficient exhausting of fluid from the cylinder chambers 114 and 130 respectively, so that the pistons 111 and 127 may be moved downwardly under the influence of the released compression of the springs 113 and 129 into engagement with the bottom of the cylinders 112 and 128 respectively.

It will be readily apparent from the foregoing disclosure that the extent of dwell at each end of the table stroke may be readily controlled by the throttle valves 120 and 135, respectively. The throttle valves 120 and 135 respectively serve to control the speed of upward movement of the pistons 111 and 127 during table reversal so as to delay the shifting movement of the reversing valve 25 into its reverse position. After the pistons 111 and 127 move upwardly to a predetermined extent, namely, to a position whereby the ports 115 and 131 are opened, the fluid may exhaust unrestricted through the pipe 116 or the pipe 132 into the reservoir 117.

The operation of the improved table reciprocating mechanism will be readily apparent from the foregoing disclosure. Assuming all the parts have been previously adjusted and the table 11 is traveling in the direction of the arrow as shown in the drawings, that is, toward the left, this movement will continue until the dog 92 engages the stud 90 on the reversing lever 85 and moves it in a counterclockwise direction. This movement of the reversing lever by actuation of the table dog 92 serves to move the valve stem 28 which shifts both the valve pistons 29 and 30 and also the reversing valve 32 until the reversing valve piston 34 closes the exhaust ports 48 and 48a, thus stopping the table movement. During this movement of the valve parts, the capacity of the valve chamber 100 increases so as to allow the released compression of the spring 113 to move piston 111 into its lower position (Fig. 2), exhausting fluid from the chamber 114 through the pipe 102 and the port 101 into expanded valve chamber 100. This takes place before the valve piston 29 closes

the port 101. The admission of fluid under pressure to the cylinder chamber 130 causes an upward movement of the piston 127 at a rate controlled by the needle valve 135. During this movement, the parts of the valve 25 move at a slow controlled rate as governed by the dwell control unit. This condition prevails until the piston 127 moves upwardly a sufficient distance to open the port 131 and thereby to allow unrestricted exhaust of fluid through the pipe 132. At this time fluid under pressure in the passage 36 of the valve 25 passes through the port 103 into the valve chamber 100 and due to the differential in piston areas causes the reversing valve 32 to move rapidly toward the right to throw it into a reverse position. In the reverse position, fluid under pressure within the chamber 32 of the valve 25 may pass through the valve chamber 47 and out through the port 46, the pipe 45, the passage 44, the hollow piston rod 18, into the cylinder chamber 43 to start the movement of the table 11 toward the right.

The movement of the table continues toward the right until the reversing dog 91 engages the stud 93 which is now in position 90a and shifts the reversing lever 85 from the broken line position 85a in a counterclockwise direction, as shown in the drawings. This movement of the reversing lever 85 serves to move both the valve stem 28 and the reversing valve 32 toward the left until the reversing valve piston 34 again closes the ports 48 and 48a, thus preventing further exhaust of fluid from the cylinder chamber 42. In this position of the reversing valve, fluid within the chamber 36 of the valve 25 passes through the port 103, the pipe 102, into the dwell control valve cylinder chamber 114 to move the dwell control piston 111 upwardly. The speed of the upward movement of the piston 111 is governed by the needle valve 120. The upward movement of the piston 111 continues until the piston 111 reaches the position illustrated in the drawings to uncover the port 115 so as to allow a substantially unrestricted exhaust of fluid through the pipe 116 into the reservoir 117.

When the reversing valve parts reach the latter position in their movement toward the left, fluid within the valve passage 36 may pass through the port 108 into the valve chamber 105 and due to the differential areas of the pistons 35 and 30, serves to cause the reversing valve 32 to move rapidly toward the left so as to admit fluid under pressure through the port 39, the pipe 40, the passage 41, the hollow piston rod 17, into the cylinder chamber 42 to start the movement of the table 11 toward the left.

It will be readily apparent from the foregoing disclosure that the upward movement of the pistons 111 and 127, as regulated by the needle valves 120 and 135 respectively, serves to provide an adjustable dwell at each end of the table stroke by retarding the shifting of the reversing valve into a reverse position for a predetermined but adjustable time interval. The dwell at either end of the table stroke may be readily varied by manipulation of the needle valves 120 and 135.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the ac-

companying drawings is to be interpreted as illustrative and not in a limiting sense.

I claim:

1. In a hydraulically operated table reciprocating mechanism, a longitudinally reciprocable table, a piston and cylinder therefor, a source of fluid under pressure, a piston type reversing valve comprising a slidably mounted valve member having a pair of spaced valve pistons thereon, a reversing valve slidably supported on said member having a plurality of spaced integrally formed pistons, a valve chamber formed at each end of the reversing valve between the reversing valve and said spaced pistons respectively, table actuated means to shift the valve member and the reversing valve to shift the reversing valve to a central position so as to cut off exhaust of fluid from the table cylinder, means to admit fluid under pressure to one of said valve chambers to shift the reversing valve into a reverse position, and means to provide a predetermined back pressure in the other valve chamber to prevent the shifting of the reversing valve into a reverse position for a predetermined but adjustable period of dwell during reversal of the table.
2. In a hydraulically operated table reciprocating mechanism, a longitudinally reciprocable table, a piston and cylinder to reciprocate said table, a source of fluid under pressure, a piston type reversing valve comprising a slidably mounted valve member having a pair of spaced pistons thereon, a reversing valve slidably supported on said member having a plurality of spaced integrally formed pistons, a valve chamber formed at each end of the reversing valve between the reversing valve and said spaced pistons, adjustable table dogs, a reversing lever actuated thereby to shift said valve member and reversing valve to shift the reversing valve to a central position so as to cut off exhaust of fluid from the table cylinder, means to admit fluid under pressure tending to shift said valve into a reverse position, and a dwell control device arranged to provide a back pressure in the other end chamber for a predetermined but adjustable time interval to prevent shifting of the reverse valve into a reverse position until after a predetermined period of dwell.
3. In a hydraulically operated table reciprocating mechanism, a longitudinally reciprocable table, a piston and cylinder to reciprocate said table, a source of fluid under pressure, a piston type reversing valve comprising a slidably mounted valve member having a pair of spaced pistons thereon, a reversing valve slidably supported on said member having a plurality of spaced integrally formed pistons, a valve chamber formed at each end of the reversing valve between the reversing valve and said spaced pistons, adjustable table dogs, a reversing lever actuated thereby to shift said valve member and reversing valve to shift the reversing valve to a central position so as to cut off exhaust of fluid from the table cylinder, means to admit fluid under pressure to one of said end chambers to apply pressure tending to shift said valve into a reverse position, and an independent dwell control device for each end of the table stroke, and independent connections between said valve chambers and said devices, one of said devices being operative at each reversal of said valve to delay shifting of said reversing valve into a reverse position for a predetermined time interval.
4. In a hydraulically operated table reciprocating mechanism, a longitudinally reciprocable table, a piston and cylinder to reciprocate said table, a source of fluid under pressure, a piston type reversing valve comprising a slidably mounted valve member having a pair of spaced pistons thereon, a reversing valve slidably supported on said member having a plurality of spaced integrally formed pistons, a valve chamber formed at each end of the reversing valve between the reversing valve and said spaced pistons, adjustable table dogs, a reversing lever actuated thereby to shift said valve member and reversing valve to shift the reversing valve to a central position so as to cut off exhaust of fluid from the table cylinder, means to admit fluid under pressure to one of said end chambers to apply pressure tending to shift said valve into a reverse position, and an independent dwell control device for each end of the table stroke, and independent connections between said valve chambers and said devices, one of said devices being operative at each reversal of said valve to delay shifting of said reversing valve into a reverse position for a predetermined time interval.

2,471,688

9

cating mechanism, a longitudinally reciprocable table, a piston and cylinder to reciprocate said table, a source of fluid under pressure, a piston type reversing valve comprising a slidably mounted valve member having a pair of spaced pistons thereon, a reversing valve slidably supported on said member having a plurality of spaced integrally formed pistons, a valve chamber formed at each end of the reversing valve between the reversing valve and said spaced pistons, adjustable table dogs, a reversing lever actuated thereby to shift said valve member and reversing valve to shift the reversing valve to a central position so as to cut off exhaust of fluid from the table cylinder, means to admit fluid under pressure to one of said end chambers to apply pressure tending to shift said valve into reverse position, a hydraulic dwell control device including a hydraulic piston and cylinder, a compression spring normally to maintain said piston in a lower position, fluid connections between the lower end of said latter cylinder and one of said valve chambers whereby fluid under pressure in said valve chamber passes into the lower end of said latter cylinder to raise said piston against the compression of said spring, a throttle valve to control the speed of movement of said piston, and a port opened after the piston has moved to a predetermined position to facilitate shifting of the reversing valve into a reverse position after a predetermined period of dwell.

5. In a hydraulically operated table reciprocating mechanism, a longitudinally reciprocable table, a piston and cylinder to reciprocate said table, a source of fluid under pressure, a piston type reversing valve comprising a slidably

10

mounted valve member having a pair of spaced pistons thereon, a reversing valve slidably supported on said member having a plurality of spaced integrally formed pistons, a valve chamber formed at each end of the reversing valve between the reversing valve and said spaced pistons, adjustable table dogs, a reversing lever actuated thereby to shift said valve member and reversing valve to shift the reversing valve to a central position so as to cut off exhaust of fluid from the table cylinder, means to admit fluid under pressure to one of said chambers to apply pressure tending to shift said valve into a reverse position, an independent hydraulically operated dwell control unit operatively connected with each of said valve chambers, each including a piston and cylinder, fluid connections between the lower end of each of said valves and said valve members respectively, an independent throttle valve to control the exhaust of fluid from the other end of each of said cylinders, a port opened after a predetermined move of said latter pistons to allow unrestricted exhaust of fluid from said latter cylinders, said throttle valves being arranged to provide a predetermined adjustable dwell at each end of the table stroke.
